UNITED STATES PATENT OFFICE.

EMMETT S. MILLER, OF PEORIA, ILLINOIS.

ELEVATOR SYSTEM.

1,216,476.

Specification of Letters Patent. Patented Feb. 20, 1917.

Application filed January 15, 1912. Serial No. 671,194.

To all whom it may concern:

Be it known that I, EMMETT S. MILLER, a citizen of the United States, residing at Peoria, county of Peoria, and State of Illinois, have invented new and useful Improvements in Elevator Systems, of which the following is a specification.

The object of my invention is, among other things,—

10 1st. To provide a simple and efficient device for automatically locking the several elevator doors located at the several floors or landings of a building, both while the elevator car is running and when at rest at an intermediate point between such floors or landings.

20 2nd. To provide a device for automatically opening any one of the several elevator doors located at the several floors or landings of a building the instant the elevator car stops opposite such floor, and for simultaneously locking the car at such point so that it cannot be started until the door is again locked in its closed position.

25 3rd. To provide a device for manually producing the initial action by which the door operating mechanism is controlled for both opening and closing the door leading to the elevator car.

30 4th. To provide a device for automatically releasing the car operating mechanism the instant the door leading to such car from any one of the floor landings is closed. In other words, more briefly put, the object of my invention is to provide means for preventing an elevator door at any of the several landings of a building, from being opened except when the elevator car is in place opposite such door, and also to so lock 40 the car controlling lever that it is impossible to start the car away from any one of the several landings of the building before securely locking the door in its closed position at such landing, whereby the liability 45 of a passenger being injured when attempting to pass to or from an elevator car is avoided, and the liability of accident from such cause is eliminated.

50 My invention is further explained by reference to the accompanying drawings, in which—

55 Figure 1 represents an inside view of the upper portion of an elevator car located in front of one of the doors leading from the landing to the car, showing also the device for opening and closing the door, located

upon the top of such car. It will be understood that a similar door is located at each floor of a building which is passed by the car; that the door in Fig. 1 is shown locked in its closed position, while the lever by which the elevator is operated, is shown as disengaged from its locking mechanism preparatory to starting the elevator either upwardly or downwardly.

60 Figs. 2 and 3, taken together, represent a plan view of the door operating mechanism carried by the car.

65 Figs. 4 and 5, taken together, represent a side view of the device shown in Figs. 2 and 3.

70 Fig. 6 is a detail showing an end sectional view of the mechanism carried by the elevator car for engaging and moving a door located at any one of the several floor landings of a building.

75 Fig. 7 is a plan view, part in section, of the device shown in Fig. 6, and

80 Fig. 8 is a detail of the device for locking the car operating lever, while the door leading to the car is in its open position.

85 Like parts are identified by the same reference numerals throughout the several views.

90 The door actuating mechanism of my device is adapted to be operated by compressed air, which air is compressed and stored ready for use by a stationary motor and compressor, preferably located near the elevator shaft. The air thus compressed, is led from the compressor to an air controlling valve 2, through a flexible duct 3, when its course is manually controlled at the will of the operator and led from such valve to the respective ends of the cylinder 4 through the ducts 95 5 and 6. 7 is an operating lever provided with a handle 7' by which the action of the valve 2 is controlled. The operating lever 7 is pivotally supported from one side of the car 8 by a supporting plate 9, screws 10 and 100 a pivotal bolt 11, and said operating lever is provided with two rigidly affixed laterally projecting arms 12 and 13, which arms are adapted to be alternately moved upwardly and downwardly as the operating lever 7 is 105 rocked on its supporting pivot toward the right and left. Motion is communicated from the arms 12 and 13 to the respective piston rods 14 and 15 of said air controlling valve, through the flexible members 16 110 and 17.

The valve 2 comprises a cylinder 18 and

a piston 19, and said piston 19 is connected at its respective sides with the said piston rods 14 and 15. The cylinder 4 is also provided with a piston 20 which is connected at its respective sides with the respective piston rods 21 and 22.

It will be understood that when the operating lever 7 is thrown toward the right, as shown in Fig. 1, the piston 19 is drawn 10 toward the left, motion being communicated from said lever to said piston through the arm 12, flexible member 16 and piston rod 14, whereby the air which enters the cylinder 18 through the duct 3, is permitted to 15 pass therefrom through the duct 5 into the cylinder 4 upon the left hand side of the piston 20, whereby the piston 20 is moved toward the right, and whereby motion is communicated therefrom through the mechanism hereinafter described, to the elevator 20 door 23, when said door is moved from the open to the closed position.

It will now be understood that by a reverse movement of the lever 7, motion 25 will be communicated therefrom through the mechanism previously described, to said piston 19, whereby the port leading to the duct 6 will be opened and the port leading to the duct 5 will be closed, when the air which is 30 led to the cylinder 18 through the duct 3, will pass from said cylinder 18 to the cylinder 4 on the right hand side of the piston 20, when said piston 20 will be moved in the opposite direction, and said door 23 will be 35 opened. It will be understood that when the piston 20 is moved toward the right by air pressure behind it, the air upon the right hand side of said piston exhausts through the duct 6 into the cylinder of the valve 2 upon 40 the left hand side of the piston 19 in said valve, and that when said piston 20 is moved in the opposite direction, the air upon the left hand side of said piston 20 will exhaust through the duct 5 into said cylinder upon 45 the right hand side of said piston 19, reference being had to Fig. 1 of the drawing. From the valve 2 the air will exhaust through ports 2' located at each end of the cylinder 18.

50 To prevent accident by starting the elevator when the elevator door 23 is open, I have provided means for automatically locking and retaining the operating lever 24, by which the elevator is started and stopped, 55 in its vertical position, while the door is open. It will be understood that when the operating lever 24 is thus locked in a vertical position, it will be impossible to start the car in either direction. The lever 24 60 is adapted to be locked in its vertical position by the bracket 25, which is pivotally supported from the side 8 of the elevator car by the supporting trunnion 26 and shaft 27, which trunnion and shaft operate in the 65 apertured lugs 28, 28, and said lugs 28 are

rigidly connected with a supporting plate 29, while said plate 29 is secured to the side of the car by the screws 30. When the bracket 25 is in the position shown in Fig. 1, the lever 24 is free to be inclined in either 70 direction on its pivotal support. When, however, the door 23 is being opened, motion is automatically communicated from the reciprocating carriage 31 to said bracket 25 through trunnion 36, carried by said carriage, bifurcated bracket 37, pivotal bolt 38, rod 39, pivotal bolt 40, arm 41, pivotal bolt 42, arm 43, pivotal bolt 44, rod 45, pivotal bolt 46, rack bar 47 and pinion 48, whereby the lever 24 is locked in its central position as 75 shown in Fig. 8, and it is obvious that as the door 23 is brought to the extreme limit of its movement toward the left, and thereby closed and locked in its closed position, the bracket 25 is simultaneously turned to the 80 position shown in Fig. 1, and thereby disengages the operating lever 24, when the operator is free to move said lever toward the right or left, and thereby cause the elevator to ascend or descend as circumstances may 85 require.

It will be understood that the teeth of the rack bar 47 engage the teeth of the pinion 48 upon the rear side of said pinion, whereby as said rack bar is moved downwardly through the mechanism described, the front of the bracket 25 will be moved upwardly to the position shown in Fig. 1, while by a reverse movement of said rack bar, said bracket 25 will be turned down 100 so that the operating lever 24 will be retained in place by and between the lugs 25' of said bracket as shown in Fig. 8. When, however, the door 23 is moved in the opposite direction, as hereinafter described, motion is communicated from the reciprocating carriage 31 to said bracket 25, through the reverse movement of said co-operating parts, whereby said bracket is turned down 105 and the lugs 25' are caused to engage said operating lever 24, whereby it becomes impossible to start the elevator in either direction so long as the door 23 remains in its open position.

Motion is communicated from the moving 115 piston 20 to the door 23 through said piston rods 21 and 22, pulley blocks 49, 49, secured to the outer end of the piston rods 21 and 22, and the two series of pulleys 50, 50. One set of each series is revolvably connected with said pulley blocks by the pivotal bolts 51 and the other set is revolvably connected to stationary brackets secured at opposite ends of rods 62, cables 52, 52, reciprocating carriage 31, to which the free ends 120 of the cables 52, 52 are attached, and block 36', which block 36' is slidably supported in said trunnion 36, and is adapted to be moved laterally or at right angles to the reciprocating carriage 31, as soon as the door 125 130

is opened and remains in such position until the door is again closed, reference being had to Fig. 7, whereby said block 36' is caused to enter the space 53 between the stationary bracket 54 and the inclinable bracket 55, and as said carriage 31 is moved toward the right, said block 36' is adapted to engage against said bracket 55, whereby said bracket is brought at right angles to its supporting plate 56, carried by said door, latch 70 will be disengaged from the catch 88, when said door will be moved by said block 36' toward the right with said carriage 31. The plate 56 is adapted to be connected with the door 23 through the plate 56' which plate is provided with apertures 57' for the reception of fastening bolts. It will be understood that the laterally moving block 36' is forced forwardly, and normally retained between the brackets 54 and 55 by the recoil of the spiral spring 58. Spring 58 surrounds and is supported from the block 36' within the hollow trunnion 36, and said spring is adapted to bear at one end against the shoulder 60 of said block 36' and at its other end against the shoulders 61 of said hollow trunnion, whereby said block 36' is forced out by the recoil of said spring.

It is preferred to make several turns of the cords 52 around the sets of pulleys 50, so that the ends attached to the block 31, will have the full movement of the door 23 with a comparatively short operating cylinder 4.

The carriage 31 is slidably supported on the parallel rods 62, 62, and said carriage is adapted to move a distance corresponding with the movement of the elevator door as it is opened and closed. When the door is being closed and has reached the extreme limit of its movement, the arm 63 of the bell crank lever 64 is brought in contact with the stop 65, mounted upon said rods 62, whereby the opposite arm 66 of said bell crank lever is moved rearwardly, whereby the block 36' is disengaged from said brackets 54 and 55. The withdrawal of the block 36' is solely for the purpose of preventing any possibility of its striking the brackets 54 or 55 of the several elevator doors, or any other obstructions, as the car moves up or down the shaft.

The sliding block 36' is provided with a recess 67 for the reception of the arm 66, which arm engages therein as said block 36' is moved in either direction. The hollow trunnion 36 is provided upon one side with a longitudinal slot 67' for the reception of the arm 66 of said bell crank lever.

I have thus far described that part of the device which is used for automatically opening and closing the elevator door, and for locking the elevator lever by which the movement of the elevator car is controlled. It will, however, be understood that to pre-

vent accident, it becomes necessary to lock the several elevator doors, located at the several landings of a building, in their closed position so that they cannot be accidentally opened until the elevator car is brought directly opposite them. To accomplish this object, I have pivotally connected one of the brackets 55, carried by the several elevator doors, with such doors and the door locking mechanism, whereby, as the door moving mechanism is brought against said movable brackets, said bracket will be turned a partial revolution upon its supporting pivots when motion will be communicated therefrom to said door locking mechanism, whereby the same will be released the instant the door starts to open, as hereinafter described.

70 is a latch which is carried by the door 23, and the same is adapted to engage at 85 its protruding end in a catch 88 supported from the door frame 72. Motion is communicated from the bracket 55 to said latch 70 through the lugs 74, pivotal bolt 75, arm 76, pivotal bolt 77, bifurcated arm 78, pivotal bolt 79, arm 80, forming one of the members of the elbow crank lever 81, pivotal bolt 82, arm 83, pivotal bolt 84, rod 85, and pivotal bolt 86. The latch 70 is connected at one end to the door 23 by the pivotal bolt 87, and said latch is yieldingly held in position to automatically engage the catch 88 by the spring 89, whereby, as the door is moved to its closed position, said latch will engage said catch, and whereby 100 the door is securely locked in its closed position until said latch is again raised and disengaged from the catch by the action of the door moving mechanism hereinbefore described.

The flexible members 16 and 17 are movably supported at intermediate points between the lever 12 and the piston rods 14 and 15, by the rollers 90, 90, and 91, 91, whereby a reciprocating movement is communicated to said piston rods from the rocking movement of said lever.

Operation.

When it is desired to stop the car 23 at 115 a landing the operating lever 24 is brought to a vertical or central position as shown in Fig. 1. To open the door the handle 7' is turned to the left which causes the piston 19 to move to the right and uncover 120 the port of duct 6. Compressed air is thus admitted to cylinder 4 back of piston 20 which is forced to the left causing the block 31 to be moved to the right by the cable 52 secured thereto. The initial movement 125 of the block 31 allows the block 36' to move out into the path of the brackets 54 and 55. At the same time the trunnion 36 of the block 31 rocks the bifurcated bracket 37 to the right and by means of rod 39, lever 130

arms 41 and 43, rod 45, rack 47 and pinion 48 brings the lugs 25' of the bracket 25 into the path of the lever 24 thus locking it, as clearly shown in Fig. 8. A slight further movement of the block 31 causes the block 36' to engage the bracket 55 and swing it toward the right as shown in Fig. 7, thereby raising the latch 70 by means of link 78, arms 80 and 83 and rod 85. The door 23 is now free to be opened and as the block 31 continues to the right it moves the door with it by means of block 36' bearing against the bracket 55 secured to the top of the door.

15 To close the door again the handle 7' is turned to the right thus moving the piston 19 to the left and admitting compressed air, through duct 5, back of cylinder 20 forcing it to the right and causing block 31 to move to the left against the stop 65. In the closing movement the block 36' bears against the bracket 54 and releases the bracket 55 thereby allowing the latch 70 to drop into a position where it will engage the catch 88 when the door is closed. Just before the stop 65 is reached the trunnion 36 engages the bifurcated bracket 37 which by further movement of the block 31 to the left, is turned up, as shown in Fig. 1, thus 30 releasing the lever 24. The final movement of block 31 withdraws the block 36' from the path of the bracket 54 and 55.

While the motor and air compressor by

which air is compressed for opening and closing the elevator door, are preferably located near any one of the several floors adjacent to the elevator shaft, said motor and compressor may, if desired, be carried by the elevator car, in which case the motive power may be communicated to the motor by an electric current through suitable conductors in the ordinary manner.

Having thus described my invention, what I claim as new and desire to secure by Letters Patent, is—

In an elevator system of the class described, the combination of an elevator shaft, an elevator car suspended in said shaft, an elevator door located at a landing of said shaft, means for automatically locking the elevator door in its closed position, air actuated means carried by the car, a latch opening member and a bracket carried by the door, a pin operable by said air actuated means adapted to engage the latch opening member to open the door and to engage the bracket to close the door, a stop and means engageable with said stop arranged to withdraw the pin from the path of the bracket and the latch member.

In testimony whereof I affix my signature is the presence of two witnesses.

EMMETT S. MILLER.
